UNITED STATES PATENT OFFICE

155,779

DESIGN FOR A LIGHTING FIXTURE

Milton S. Carstens, Glencoe, Ill.

Application April 30, 1947, Serial No. 138,693

Term of patent 3½ years

(Cl. D48—23)

To all whom it may concern:

Be it known that I, Milton S. Carstens, a citizen of the United States, residing at 1 North La Salle Street, Chicago, in the county of Cook and State of Illinois, have invented a new, original, and ornamental Design for Lighting Fixture, of which the following is a specification, reference being had to the accompanying drawings, forming part thereof.

Figure 1 is a perspective view of a lighting fixture, showing my new design;

Figure 2 is an end elevational view;

Figure 3 is a fragmentary cross sectional view taken on the line 3—3 of Figure 2; and

Figure 4 is a fragmentary cross sectional view taken on the line 4—4 of Figure 2.

I claim:

The ornamental design for a lighting fixture, as shown.

MILTON S. CARSTENS.
